G. W. LALLY:
DUMPING WAGON HOIST.
APPLICATION FILED NOV. 20, 1915.

1,355,763.

Patented Oct. 12, 1920.

UNITED STATES PATENT OFFICE.

GEORGE W. LALLY, OF EVERETT, MASSACHUSETTS, ASSIGNOR TO THE LALLY COMMERCIAL BODY COMPANY, OF EVERETT, MASSACHUSETTS, A CORPORATION OF MASSACHUSETTS.

DUMPING-WAGON HOIST.

1,355,763.

Specification of Letters Patent. Patented Oct. 12, 1920.

Application filed November 20, 1915. Serial No. 62,502.

To all whom it may concern:

Be it known that I, GEORGE W. LALLY, a citizen of the United States, and resident of Everett, county of Middlesex, and State of Massachusetts, have invented an Improvement in Dumping-Wagon Hoists, of which the following description, in connection with the accompanying drawings, is a specification, like numerals on the drawings representing like parts.

My present invention is an improved hoist for dumping wagon bodies, particularly intended for use in automobile trucks with a carrying capacity of several tons. The object of my invention is to enable a simple and powerful hoist capable of handling very heavy loads to be utilized in the modern type of automobile truck, wherein the extra lifting power requisite in the first tilting action of the body may be secured and the further tilting of the dumping body is also effected through the same lever. In order to render a dumping vehicle body of the type herein illustrated of strong and simple construction, it is necessary to arrange the entire hoisting mechanism between the wagon frame and the bottom or sill of the movable body, thus insuring a low center of gravity and compact construction. However, considerable difficulty has been found in devising suitable and sufficiently powerful hoisting devices which can be folded within the short space allowed between the vehicle frame and wagon body sills. In using levers for this hoisting mechanism it is necessary to employ a relatively short lever or arm to conserve the hoisting power while initiating the lifting or tilting of the body, although after the body is once partially tilted a longer lever and quicker utilization of the hoisting power can be advantageously employed. As the speed with which a dumping body can be hoisted and its load discharged are of great importance, while the power available is only that manually applied by the driver or operator to a hand crank, the difficulties of the hoisting problems in this type of heavy load-carrying vehicles will be appreciated. These difficulties are increased in the modern automobile truck wherein a load of many tons is ordinarily to be handled. In my present invention I have utilized a type of bent arm hoist shown in the

copending application of Robert W. Rose, Serial No. 46,657, filed August 21, 1915, and also employ, preferably a wedge type of bearing during the initiation of the tilting movement, such for example, as illustrated in my prior Patent No. 1,158,813, issued November 2, 1915, although the bent arm type of hoist I utilize may be employed without this middle wedge feature.

Other novel features of the invention, combinations of parts, details of construction and advantages will be hereinafter more fully described and claimed.

In the accompanying drawings illustrating a preferred embodiment of the invention as applied to an automobile truck,

Figure 1 is a side view illustrating the initial position of the hoist and the final position, as shown in dotted lines;

Fig. 2 is a plan view with the dumping body removed.

I have herein illustrated the hoist in connection with a turntable mechanism of novel form and suitable to carry a heavy load of approximately ten tons of coal, capable of discharging such load at the rear or either side of the truck, and with the center of gravity of the dumping body both with its load and when empty, carefully centered at a low point over the rear wheels of the truck and turntable, when the body is in raised position.

An automobile chassis is shown in conventional form, comprising the side frames 1, engine 2 and seat 3 at the forward end of the truck, with the dumping body and hoisting mechanism arranged to be carried principally by the rear wheels, and when raised to inclined position to be centered over the rear axle 4. A dumping body 5 is mounted upon sills 6 at each side of the vehicle, and the hoist frame includes a pair of supporting members 7, said frame being pivoted at 8 upon each side to the sills 6 of the dumping body. The frame 7 also is mounted upon the upper member 9 of the circular turntable supported by a plurality of short braces 10, the corresponding lower turntable bearing 11 being fixed directly upon the support 12, carried by the vehicle side frames 1. This turntable construction is centered over the rear driving wheel axle 4, and the entire body, frame 7 and hoisting mechanism to be described is adapted to

swing and turn upon said turntable so as to discharge the load at any point desired within the range of swinging movement from one side to the other of the truck.

5 At the forward end of the side frame 7 is a cross bar 13, firmly uniting the sides of frame 7 and carrying the forward ends 14 of the side tracks 15, said tracks being preferably of angle iron and extending horizontally from the cross bar 13 to the point 10 16 and thence at an angle to the top of the frame 7 at 17, on each side. At the forward end of the frame 12 are rollers 18 supported on which the cross bar 13 of the frame rests and rolls. These rollers bear 15 the weight of the dumping body 5 at the forward end when said body is in lowered position, supporting the front end of the body, its load and the forward part of the 20 frame and hoisting mechanism. The rollers 18 are preferably wide to insure bearing of the cross bar 13 thereon during swinging of the frame and dumping body about the center 19 of the turntable. Each roller is 25 firmly supported, bearings therefor in the cross frame 20 being provided as indicated at 21, Fig. 1, and in brackets as shown at 22 on the side frames 12.

The hoisting mechanism comprises a pair 30 of bent arm levers, each with an arm 23, and an arm 24 extending substantially at right angles with each other. At the elbow of the bent arm levers is a shaft 25 extending through each arm and carrying 35 rollers 26 on its opposite ends adapted to bear directly against the lower portion of the sills 6 on the body 5. A similar shaft 27 unites the forward ends of the arms 23 and carries rollers 28 on its opposite ends 40 which bear upon the track 14. Each of the rollers may have small flanges as indicated at 29. The ends of the arms 24 are each pivotally united to the body, preferably with links 30 by a shaft 31, which links have 45 their opposite ends pivoted on a rod 32, which rod is fixed to the sills of the dumping body 5, passing through a lower bar 33 bolted to the sill 6 and acting as a guard or flange to retain the rollers 26 and fitting snugly within the side frame 7 when 50 the body is in lowered position. Cross braces 34 and 35 are bolted to the bent arm hoisting levers substantially as illustrated in Fig. 2. I prefer to utilize a wedge member 36 at each side of the dumping body 5, which wedge will receive the initial thrust of the arms 23 of the hoisting levers, the rollers 26 on the shaft 25 at the elbow of the levers bearing first upon the wedge 36 during 55 the initiation of the tilting or lifting movement and thus taking the direct thrust of the arms 23. These wedges 36 may have a contour appropriate for the power supplied and load to be lifted to coöperate with 60 65 the angle of the arms 23.

To manipulate the bent arm levers I provide a shaft 37 to which the ends of chains or the like 38 are wound, having their other ends secured to the rod 27 at the forward end of the levers. The levers are thus moved 70 by winding up the chains 38 through the rotation of the shaft 37. A suitable train of gears 39, 40 and 41 is provided, the shaft of the gear 41 being equipped with a hand crank 42, as is customary. A chain 43 secured to the frame 7 at one end and to the sills of the body 5 at its other end is of proper length to limit the hoisting action until the tilting of the body 5 will bring said body and its load in position substantially with its center of gravity over the center 19 of the turntable.

The operation of the hoist will be readily understood. Manipulation of the hand crank 42 and the train of gears rotates the shaft 85 37 winding up the chains 38. These chains are led under the shaft 31, tending to give a slight upward thrust through the links 30, while moving the hoisting levers forwardly with the rolls 28 rolling upon the straight 90 portions of the tracks 15 at either side and with the rolls 26 bearing upon the wedges 36. The engagement of the links 30 insures the continuance of the thrusting action of the side levers 23 directly upon the wedges 95 until the tilting body 5 is inclined considerably and the heaviest work of the hoisting action is completed. The continued winding up of the chains 38 and movement of the bent arm levers 23 and 24 brings the 100 end portions of the arms and the sides of the links 30 into engagement directly on the bottom of the sills 6 at 45 where the levers are held by the links 30 and the completion of the tilting action is carried on 105 by the movement of the rolls 28 on the inclined portion of the tracks until they have reached the limit of movement at the point 17 when the chains 43 will act as a stop. With the tilting body in this position, centered over the turntable, it may be swung at either side to discharge the load at an angle, the frame support and hoisting mechanism swinging with the body 5 around the turntable and across the rolls 18, sufficient 110 clearance being provided by both the forward portion of the frame and the rearward inclination of the dumping body 5 to permit of lateral swinging entirely around the turntable from one side position to the other. When the body and frame have been swung to desired position, the load is then discharged, and the empty wagon body and frame will still be balanced over the turntable, being easily swung backwardly into 115 normal position in alinement with the automobile truck, the frame resting upon the rollers 18. In this position the body is then lowered and the normal center of gravity of the lowered tilting body will hold it in 120 125 130 135

downward position without catches, locks, or the like, and in position to receive another load.

My invention is further described and defined in the form of claims as follows:

1. Hoisting mechanism for a dumping body of the kind described, comprising a pair of side levers, each formed by two arms substantially at right angles to each other, a link pivotally connecting one of said arms in each lever to the movable portion of the dumping body, wedges bearing on said body adapted to receive the initial lifting thrust of the other arm of the levers and means to move the pair of levers in unison whereby the first tilting movement is effected through the lifting action of one of said lever arms and the final portion of the tilting movement is produced by the thrust of both arms of the levers, each lever having an anti-friction bearing at the right angled elbow traveling on the wedge.

2. In a hoisting apparatus of the kind described, a pair of bent arm levers adapted to effect the hoisting action, each lever comprising two arms extending substantially at right angles to each other, a link connection for one arm, to the article to be raised, wedges adjacent said link connection and means to secure the lifting action of one of the lever arms on the wedges during the preliminary hoisting actuation of said levers, the bearing of the levers on their respective wedges being at the right angled elbow of each lever.

3. Hoisting apparatus of the kind described, comprising a pair of bent arm levers adapted to effect the hoisting action, each lever consisting in two portions rigidly secured together extending substantially at right angles to each other, a link connection for one of said portions to the article to be raised, an anti-friction bearing for the lower end of each lever, a rod connecting said pair of levers at the right angle elbow portion carrying a roller bearing on the body, flexible chains attached to the free ends of said levers, and leading under said link connecting means and thence upwardly to a shaft on which said chains are wound, said shaft being journaled above the normal lowered position of said link and lever connection, whereby the winding of such chains will exert a lifting tension at the elbow of each lever and simultaneously with the thrusting strain on the outer ends of said levers.

4. In a hoisting apparatus of the kind described, a pair of bent arm levers adapted to effect the hoisting action, each lever comprising two arms extending substantially at right angles to each other and normally bearing on the apparatus to be hoisted at the angle joining said two levers, a link connection for one arm, to the article to be

raised, wedges adjacent said link connection and means to secure the lifting action of one of the lever arms on the wedges during the preliminary hoisting actuation of said levers, together with means for completing the hoisting action through the movement of both arms of each lever in approximately a vertical hoisting position.

5. A vehicle hoist of the kind described, comprising a vehicle chassis, a turntable carried by said chassis, a frame mounted on said turntable, a dumping wagon body pivotally mounted on said frame, hoisting mechanism between the frame and dumping body, including a pair of bent arm levers, each arm extending substantially at right angles to its adjacent arm, rolls on the forward ends of said levers, a track for each lever, carried on the frame and including a straight portion and an inclined portion, pivotal link connections on the ends of the lever arms opposite to said roll carrying arms, roller bearings on the elbows of each bent arm lever adapted to impart preliminary hoisting to said dumping body during the first movement of the hoisting levers on the tracks, means for the link ends of said bent arm levers to take up the further hoisting action and complete the same, together with means to move the levers in unison, to produce both the preliminary thrusting from the elbow bearings of the bent arm levers and the completion of the hoisting as a continuous actuation.

6. Hoisting apparatus of the kind described, comprising a vehicle, a dumping body pivoted thereon, hoisting mechanism to raise said body angularly with relation to the vehicle, said mechanism including a pair of movable levers, one at each side of the dumping body, each lever formed by two integral arms extending rigidly substantially at right angles to each other, links pivotally connecting the body to one end of said arms, anti-friction means bearing between the other end of the arms and the vehicle, an inclined path on the vehicle for the hoisting levers to follow, a shaft mounted above the normal lowered position of said pivotal connection between said levers and links, a pair of chains arranged to be wound upon a shaft to actuate the levers and so positioned and arranged as to be completely wound upon the shaft when the hoisting levers have completed their lifting movement with the said pivotal links bearing against the bottom of the vehicle body.

In testimony whereof I have signed my name to this specification in the presence of two subscribing witnesses.

GEORGE W. LALLY.
